ADJUSTABLE GARMENT SIZER AND
STRETCHER

Margaret Dickey, Portland, Oreg.

Application December 16, 1935, Serial No. 54,689

6 Claims. (Cl. 223—69)

My invention relates to garment stretching frames, and particularly to frames on which such garments as blouses, sweaters, skirts, and one-piece knit dresses may be dried after washing, 5 in order to prevent shrinkage.

As is well known, it is necessary for such articles, especially when made of wool, to be stretched on a frame, and their normal size maintained while they are drying, if shrinkage 10 is to be satisfactorily prevented. Such frames are also used not only when knitted garments of wool or silk are to be dried after washing, but also when such garments, even without washing, need to be stretched or "sized" to conform better 15 to the shape of the person who is to wear them.

The blouse and sweater stretchers heretofore provided, in my opinion, are not practical; for example being cumbersome or complicated to set up; or having hinge elements or other parts 20 which tend to catch in the material to be stretched or to cause unsightly marks and creases to be left in the material; or not being properly shaped to conform to the shape of the blouse or sweater; and, furthermore, with no provision 25 made for stretching a blouse or sweater at the bust; and besides, being so expensive to manufacture that they cannot be sold to meet the popular demand. Similar criticism may be made of, 30 one-piece dress stretchers and of skirt stretchers, which furthermore are adapted to be used for one size garment only.

The object of my invention is to provide a simple, strong inexpensive garment stretcher usable for blouses or sweaters, and having no 35 hinge elements, or other parts which are apt to catch, or mark the garment; and further, having arm sections which may be detached and arranged inverted over the body of the blouse 40 stretcher section when the stretcher is not in use, thus to enable the arranging of the garment stretcher as a whole in compact form for laying aside.

Another object of my invention is to provide 45 a garment stretcher composed of separate skirt and blouse sections, adapted to be used together, as for a one-piece dress, or separately for either blouse or skirt.

A further object of my invention is to provide 50 a garment stretcher which will include a simple practical skirt stretcher which may be adjusted for various widths at the top, and at the bottom of the skirt.

Another object is to provide a blouse stretcher 55 adjustable both at the neck and the waist lines,

and independently of the size to which the skirt stretcher is adjusted.

A further object of my invention is to provide, for the blouse section of my garment stretcher, a detachable bust-stretcher section, thus making 5 possible a more accurate shaping of the garment, particularly when to be worn by a larger woman; and such bust stretcher section to be adapted for shaping a blouse or sweater with high or low bust. 10

The above mentioned objects and other incidental features of my invention I attain by the construction of my stretcher hereinafter fully described, with reference to the accompanying drawings, in which:

Fig. 1 shows my garment stretcher as composed of separate blouse and skirt sections, detachably connected, and including a bust former detachably mounted on the blouse section;

Fig. 2 illustrates the blouse section of my 20 stretcher with the arm pieces removed, and arranged inverted, and folded one over the other within the blouse section, thus placing the blouse section in compact form;

Fig. 3 is a fragmentary view showing one of 25 the arm pieces of the blouse section arranged in its extended position, thus illustrating how the blouse stretcher is set up ready for use;

Fig. 4 shows, on a larger scale, the construction of the inner ends of the arm pieces, whereby the 30 inadvertent displacement of the arm pieces either folded inward or extended is prevented;

Fig. 5 shows a fragmentary section on the line 5—5 of Fig. 4; and

Figs. 6 and 7 show, respectively, side elevations of the bust former section of my garment 35 stretcher; Fig. 6 illustrating the bust former section as arranged for high bust; and Fig. 7 as arranged for low bust.

My garment stretcher consists of three separate 40 parts, the blouse section A, the skirt section B, and the bust former section C.

Describing first the blouse section A, with reference to Figs. 1, 2, 3, 4 and 5:

The blouse section consists of a wire frame 45 made of two parts *a* and *b* relatively adjustable to increase or diminish this section in width. That is to say, the ends *a'*, *b'*, *a²*, *b²*, of the wires composing the two frame parts are adjustably connected at the neck and waist lines by sliding 50 said ends one on the other; the flat metal loops *c*, *c'*, *c''* provided on the wire ends *a'* and *b²* of one of said frame parts forming guides for the wire ends *a²*, *b'* of the other frame parts to slide 55 in, and the frame parts *a*, *b* being secured in ad-

justed position by thumb screws *d*, *d'*. Thus the width of the blouse section can be adjusted at the neck and the waist lines independently as required. A suspending hook *e* is provided at the neck of the blouse body section.

5 The arm pieces *f* and *g* of the blouse section are preferably made of spring wire in the shape shown by Figs. 2 and 3. The inner end of each arm piece is preferably made with an outwardly 10 curved portion *h*, a locking notch *i*, and a locking abutment or retaining lug *j* shown in Figs. 2 and 4. At the side of the blouse body section are provided loops *k* thru which the arm pieces may be inserted, extended, or inwardly folded within 15 the blouse body section.

The insertion of the arm pieces *f*, *g*, thru the loops *k* is readily done by springing the longitudinal portions of the arm pieces together as indicated by dotted lines in Fig. 3. When the arm 20 pieces are inserted in the loops *k*, the lock notch *i* at the upper inner end of each arm piece will be engaged with the upper end of the loop *k*, and the abutment *j* at the lower inner end of each arm piece will be engaged with the lower end of 25 the loop *k*; and thus inadvertent displacement of the arm pieces, when arranged in either of their said positions, will be prevented. Said arm-piece-locking means also prevents their being pushed inward when the sleeves of the blouse are 30 pulled over them. Also prevents the arm-pieces from being pulled inward by the pull of the arms of the blouse. By making the arm pieces removable the blouse body section may be used without any arm pieces, if desired, and similarly; 35 also, an arm piece may be used separately without the blouse stretcher section, if desired.

The length of the arm pieces, between their extremities, should be such that when the arm-pieces are arranged in extended position their 40 outer ends will terminate at the top of the wrist portions of the blouse sleeves, and so that the wrist portions of the blouse sleeves will hang free and loose beyond the outer ends of the arm pieces. This arrangement insures that the wrist 45 portions of the blouse sleeves will not be stretched in drying. And, furthermore, the wrist portions of the blouse sleeves may be pinned beyond the outer end portions of the arm pieces, and in that way the blouse sleeves may be stretched and dried 50 to desired length, and also shrunk to their original slenderness.

The outer ends *f'*, *g'* of the arm pieces may also be slightly reduced in width, so that the wrist portions of the blouse sleeves will not be stretched. 55 The skirt section, shown by *B* in Fig. 1, is preferably made of two parts, *l* and *m*, slidably, adjustably connected at top and bottom by guides *n* and secured in place by thumb screws *o* in similar manner as already described in reference 60 to the blouse body section. Thus the adjustments for waist line and the bottom hem line of the skirt stretcher may be made independently. The top of the skirt stretcher may be provided with flat metal hooks *p*, or some other convenient 65 means, for detachably supporting the skirt stretcher section from the blouse section.

In using my adjustable blouse body stretcher section, the latter should be adjusted in width so that the measurement across the bust will be approximately two inches larger than the actual measurement across the bust of the person to wear the blouse. And, likewise, in using the adjustable skirt section of my garment stretcher, the same should be so arranged that the measurement across the hip of the skirt indicated by 70

the dotted line *x*—*x* in Fig. 1 will be approximately two inches greater than the actual measurement across the hips of the person to wear the skirt. The said arrangement of the blouse section and the skirt section of my garment 5 stretcher is necessary in order that the blouse and skirt will fit the person comfortably and properly.

A simple, non-adjustable skirt stretcher section may be made of wire in the form of a skeleton 10 frame conforming to the outline of the skirt, where the stretcher is to be used by one person only. But, in making such one-piece skirt stretcher frame, the top of the skirt stretcher must correspond to the exact measurement of 15 the waist line of the person to wear the skirt, and the side portions of the stretcher frame should curve outwardly, downwardly from said waist line to the hip line, indicated by the dotted line *x*—*x* in Fig. 1; and the cross measurement 20 at said hip line should be approximately two inches larger than the actual hip measurements of the person to wear the skirt. But preferably the skirt stretcher frame should be made so that it can be adjusted as to width as above described, as thus to be usable for skirts of different sizes. 25

If the top of the skirt is provided with a rubber band, the skirt, in being placed on my skirt stretcher, should be so arranged that the waist 30 band portion of the skirt will be located above the top of the skirt stretcher frame.

The bust former section indicated by *C* in Fig. 1, and shown also in Figs. 6 and 7, may be made of cross wires *q*, *r* and diagonal wires *s*, the wires 35 being welded or soldered together. The said wires are so shaped as to give the bust former section the desired bust forming contour, and the bust forming contours are so located with reference to ends of the bust former section as to 40 adapt the latter to be reversed, and arranged as suitable for either a high bust or low bust contour.

The bust former section is made of such length as to extend from neckline to waistline of the blouse section, and the upper and lower ends of 45 said bust former section are made with hooks *t* and *t'*, respectively, adapted to be engaged with the neck and waist line parts of the blouse section, as shown more clearly in Figs. 6 and 7. The 50 bust former section arranged as shown in Figs. 1 and 6 is for a normal or high bust figure. But for a low bust figure the bust former section would be attached to the blouse section in inverted position, as indicated by Fig. 7. Thus my 55 blouse stretcher section may be arranged to impart a high or low bust contour to the blouse, or with straight front without bust (by omitting bust former section altogether).

The diagonal wires *s* of the bust former afford 60 efficient means of shaping or stretching V-neck sweaters, since the V-neck may be pinned to these wires by rust-proof pins, while the garment is drying. Blouses or sweaters with surplice style front may also be accurately shaped in front by 65 pinning overlapping front parts of the blouse to the said diagonal wires. The bust former is also made with semi-circular loops of wire *t* and *t'* at top and bottom for the shaping of rounded neck lines in front when the bust contour is required. Any marks made in the garment by the pinning are easily removed, after the garment is dry and stretching has been completed, by steaming such places lightly with a damp cloth placed 70 between the garment and a hot iron. 75

The foregoing description gives one practical embodiment of my invention in a two-piece adjustable garment sizer and stretcher. The blouse and skirt sections may be used separately for 5 blouses and sweaters, or skirts, or used together for a single dress; and the blouse section may be used with or without the bust former C. All sections of my stretcher are preferably made of heavy rust-proof wire. In actual practice I make 10 my stretchers in three sizes, the means provided for adjusting the widths of blouse and skirt sections taking care of the intervening sizes.

Modifications in construction, but still retaining the essential features of my invention, must 15 be left to the expediency of the manufacturer. The manner of using my stretcher for shaping garments on it will be apparent from the above description.

I claim:

- 20 1. A garment stretcher comprising a skirt section and a blouse body section, means detachably supporting the skirt section from the blouse body section, wire arm pieces detachably supported by the sides of the blouse body section, said arm pieces arrangeable to extend outward from the 25 sides of the blouse body section or inward within said body section, and a wire bust-forming section detachably supportable on said blouse body section.
- 30 2. A garment stretcher comprising a skirt section and a blouse body section, means detachably supporting the skirt section from the blouse body section, wire arm pieces detachably supported by the sides of the blouse body section, said arm pieces arrangeable to extend outward from the 35 sides of the blouse body section or inward within said body section, and a wire bust-forming section detachably supportable on said blouse body section, said bust-forming section being reversible 40 and adapted to provide either a high or low bust contour.

3. In a garment stretcher comprising a blouse body section made of spring wire, arm pieces of the blouse body section made of wire, the sides 45 of the blouse body section provided with loops thru which said arm pieces are inserted, for lateral extension outwardly from the sides of the blouse body section or for extension crosswise within said body section, the inner ends of said 50 arm pieces adapted to permit the longitudinal portions of the arm pieces to be sprung together, the upper inner ends of said arm pieces having a retaining notch and the lower ends of said arm pieces having an abutment, whereby said inner 55 ends of the arm pieces may be engaged with the

opposite ends of said loops of the sides of the blouse body, and inadvertent displacement of said arm pieces, when arranged in either of their said positions, is prevented.

4. In a garment stretcher comprising a blouse body section made of spring wire, arm pieces of the blouse body section made of wire, the sides of the blouse body section provided with loops thru which said arm pieces are inserted, for lateral extension outwardly from the sides of the blouse body section or for extension crosswise within said body section, the inner ends of said arm pieces including a curved transverse portion adapted to permit the longitudinal portions of the arm pieces to be sprung together, the upper 10 inner ends of said arm pieces having a retaining notch and the lower ends of said arm pieces having an abutment, whereby said inner ends of the arm pieces may be engaged with the opposite ends of said loops of the sides of the blouse body, and 15 inadvertent displacement of said arm pieces, when arranged in either of their said positions, is prevented.

5. A garment stretcher comprising a blouse body section made of wire, removable arm pieces 20 made of wire, a loop provided at each side of the blouse body section through which loop one of said arm pieces may be slidably inserted either for lateral extension outwardly from said body section or for extension crosswise within said body 25 section, the inner end of each arm piece bowed to permit the longitudinal portions of such arm pieces to be pressed towards each other, the longitudinal portions of each arm piece having 30 means for engaging the upper and lower ends of said loop when said arm piece is inserted in said loop, whereby to hold said arm piece rigidly in 35 said loop but permitting said arm piece to be slid out of said loop when the longitudinal portions of said arm piece are pressed together. 40

6. In a garment stretcher having a blouse body section a bust former attachable to said body section, said bust former made of cross wires fastened together and so shaped as to give a bust form contour, said bust former having a loop of wire at 45 the neckline corresponding to a front rounded neckline of a garment, and diagonal wires extending downward from the sides of said loop to correspond to a V-shaped neckline; whereby the neck of the garment may be pinned to the corresponding wires on the bust former and held in 50 shape when the front of said garment is stretched over said bust former.

MARGARET DICKEY. 55
